UNITED STATES PATENT OFFICE.

NATHANIEL DAVIS, OF HARBOR GRACE, NEWFOUNDLAND.

PROPELLION MECHANISM FOR WATER CRAFT.

Application filed March 26, 1926. Serial No. 97,664.

This invention relates to improvements in propulsion mechanism for water craft, and more particularly to improvements in the paddle wheel type of such mechanisms.

5 Heretofore paddle wheels carried or "lifted" a great deal of water during the upward travel of the individual paddles or blades, and even some of the water thus "lifted" was carried clear around the wheel. This 10 retarded the speed of the craft and consequently it required more power than otherwise was necessary to revolve the wheel.

The primary object of the invention is, therefore, to provide a paddle wheel propulsion mechanism which will prevent the paddles or blades from lifting water.

Furthermore, in the old type of paddle wheel the blades met the water substantially broadside, or in a "slapping" manner, which 20 also tended to waste power.

Therefore, a second important object of this invention is to provide a paddle wheel propulsion mechanism, the paddles or blades of which will cut the water at the commencement of their stroke, rather than "slap" the water.

A third important object of the invention is to provide a device of this class which may be applied to a high speed motor craft.

30 A fourth object is to provide a device of the said type which may be positioned in a craft as desired, such as aft or amidships, or in multiple.

A further object is to provide a device of the class specified which will be simple, durable, efficient, and inexpensive to produce.

These, together with other objects, may be attained by the construction, combination and arrangement of the parts as will be hereinafter more fully described, illustrated in the accompanying drawing, and pointed out in the claims hereunto annexed.

Referring to the drawing:

45 Figure 1 is a cross-sectional side elevation of a propulsion mechanism constructed in accordance with this invention, showing a vessel in outline, and a power device in a tentative location within the vessel shown in broken outline;

50 Figure 2 is an enlarged detailed cross-sectional side elevation of the paddle wheel and drum; and,

Figure 3 is an enlarged cross-sectional

detailed rear elevation of the propulsion unit.

Similar reference characters refer to corresponding parts throughout the several views.

The invention consists of a propelling unit comprising essentially a drum 12 revolvable within a horizontally disposed cylinder 13 and provided with a plurality of spaced parallel longitudinal slots 14, and a paddle wheel 15 journalled within the drum and provided with a plurality of equally spaced longitudinal paddles or blades 16 extending radially therefrom and adapted to mesh with and extend through the slots in the drum as the drum thus revolves the paddle wheel.

This unit may be situated centrally of the craft, aft or amidships or at an intermediate point, or in multiple, or in twin arrangement, as desired; one only being shown on the drawing as an example. On the drawing also is shown a vessel A in outline, as is also shown in dotted or broken lines a power device B such as an internal combustion engine for example, and for convenience in illustration is shown in the fore section of the vessel A, and as having a drive shaft C.

The cylinder 13 is rigid and may be secured to the craft structure in any convenient manner, as for example it is shown in this instance as being bolted to the flooring D of the craft. This cylinder has a longitudinal opening in its bottom part registering with a transverse opening in the flooring D, and the drum 12, which revolves within the cylinder, is exposed through these openings which are below the water line when the craft is afloat.

The paddle wheel 15 is journalled eccentrically within the drum 12, as will be hereinafter described, and the blades 16 are adapted to engage the slots 14 as the drum 12 revolves and to extend beyond the walling of the drum during its course of travel past the opening in the cylinder 13. Thus the drum imparts movement to the paddle wheel, and each blade in turn being immersed from the time it meshes with and extends through one of said slots, the craft is propelled ahead or astern according to the direction of the rotation. It will here be noted that each blade as it is immersed cuts

the water without "slap". Further, no water is "lifted" by the blades, and any small quantity of water entering the drum through the slots will be expelled therefrom by centrifugal force.

The drum 12 is provided with cored journals 17 in bearings 18 on the central part of the cylinder 13. The paddle wheel 15 is journaled on a stationary shaft 19 on hangers 20, and these hangers are provided with round horizontal portions 21 which extend through the cores in the journals 17. The shaft 19 is made rigid by outer members 22 on the horizontal portions 21, which are secured to a permanent immovable part of the craft, such as the flooring D for example.

Various transmission means may be employed to transmit power from the power device B to the propulsion unit, but as an example there is shown on the drawing a pinion E rigid on the journal 17 and meshed with a crown gear F rigid on the drive shaft C. The pinion E is cored to allow the horizontal portion 21 to pass through.

There has thus been described a simple and effective device for the purpose specified, and now having fully disclosed the nature of the invention and the manner in which it is to be performed, what I claim, is:—

1. In a propulsion device for water craft, a horizontally disposed stationary cylinder arranged transversely of the craft and having a longitudinal opening registering with a corresponding opening in the flooring of the craft, a drum fitted within the cylinder and adapted to revolve therein and having a plurality of spaced longitudinal slots in its annular walling, a paddle wheel journaled eccentrically within the drum so that the paddle blades thereof consecutively mesh with and extend through said slots to the water during the travel of the respective slotted portions of the drum between the sides of said openings, and means for revolving said drum.

2. In a propulsion device for water craft, a horizontally disposed stationary closed ended cylinder arranged transversely of the craft and having a longitudinal opening registering with a corresponding opening in the 50 flooring of the craft, a closed ended drum fitted within the cylinder and adapted to revolve therein and having a plurality of spaced longitudinal slots in its annular walling, said drum having journals in bearings 55 on the lateral wallings of the cylinder, means for revolving said drum, and a paddle wheel journaled eccentrically within the drum so that the paddle blades consecutively mesh with and extend through said slots to the 60 water during the travel of the respective slotted portions of the drum between the sides of said openings.

3. In a propulsion device for water craft, a horizontally disposed stationary cylinder arranged transversely of the craft and having a longitudinal opening registering with a corresponding opening in the flooring of the craft, a drum fitted within the cylinder and adapted to revolve therein and having a plurality of spaced longitudinal slots in its 65 annular walling, said drum having cored journals in bearings on the lateral wallings of the cylinder, horizontal members extending through said journals, hangers on the 70 inner end parts of said members, a shaft connecting the lower end parts of the hangers, anchorage members on the outer end parts of said horizontal members, a paddle wheel journaled on said shaft within the 75 drum so that the paddle blades thereof consecutively mesh with and extend through said slots to the water during the travel of the respective slotted portions of the drum between the sides of said openings, and 80 means for revolving said drum.

In testimony whereof I have affixed my signature.

NATHANIEL DAVIS.
